COMBINATION SANDER AND JOINTER

Ole Evinrude, Milwaukee, Wis., assignor to Outboard Motors Corporation, Milwaukee, Wis., a corporation of Michigan.

Original application February 27, 1933, Serial No. 658,702. Divided and this application July 13, 1934, Serial No. 734,919

10 Claims. (Cl. 51—128)

This invention relates to combination sander and jointer.

The present application is a division of my application, Serial Number 658,702, filed February 27, 1933, now Patent No. 1,973,409, dated Sept. 11, 1934.

It is the general object of the invention to provide a simple easily operated combination tool including in small compass all the equipment necessary for woodworking, with means by which the devices for performing the different types of work are available for alternative use, or may be moved to retracted positions entirely out of the way of the operator with a minimum loss of time in adjustment.

More specifically, it is the object of the present invention to provide a novel and improved means whereby a sander is made alternatively available to perform the function of a jointer, the sanding disk being interchangeable with a lathe center; and generally thereby to improve the effectiveness, facility, and safety with which a machine of this type may be adjusted and used.

It is a still further object to provide an adjustable jointing fence for use with the sander disk capable of instant movement to and from a position of work, and in which there is a suitable circular shouldered recess for the sanding disk, with adjustable means for a micrometric axial movement to position the fence guiding faces about the sander disk thereby to regulate the depth of the cut in a given transfer of work; and an independent similarly oscillating sanding table cooperatively usable with the jointer fence.

In the drawing:

Figure 1 is a perspective view of the apparatus embodying the invention as viewed from the right front quarter.

Figure 2 is a fragmentary detail of the apparatus shown in Figure 1 illustrating different positions of adjustment to which certain parts may be manipulated.

Figure 3 is a fragmentary detail in plan showing the headstock portion of the lathe and the separated accessory equipment which is normally mounted detachably thereon.

Figure 4 is an enlarged detail view showing the headstock and sanding disk in front elevation and illustrating the jointer fence and table in longitudinal section.

Like parts are identified by the same reference characters throughout the several views.

The apparatus is assembled upon a lathe frame 9 having spaced headstock bearings 10 and 11 from which the headstock spindle shaft 12 projects at both ends. Between the headstock members 10 and 11 is a step pulley 13 connected by belt 14 with the complementary step pulley 15

on the shaft 16 of the motor 17. The motor is carried on a pivoted platform 18 which is slidably adjustable as well as pivotally movable upon a short length of shafting 19 carried by the frame. The weight of the motor tends to keep the belt 14 under proper tension, and a long handle 20 projects forwardly and upwardly to a position within easy reach of the operator's hand, whereby the tension may be removed from the belt for shifting purposes and whereby also, the motor and its platform 18 may be bodily adjustable axially to register different elements of its four step pulley 15 with a given element of the three step pulley 13.

The tail stock 21 and the tool rest 22 are adjustable in the lathe bed in the usual way.

The head stock spindle 12 may be provided with the usual driving and centering point shown at 24, but may alternatively be provided with a sanding disk 25. Removably applied by adhesive or otherwise, to the face of this disk, is a corresponding disk of sandpaper 26 which serves not merely for sanding in finishing operations, but also is used as a jointer through means hereinafter to be described.

Projecting rearwardly from the headstock brackets 10 and 11 are the arms 28 and 29 in which is fixed a shaft 30 parallel to the bed of the lathe and spaced rearwardly therefrom. It is particularly to be noted that both ends of this shaft are exposed to receive for support and adjustment numerous pieces of necessary accessory equipment.

Among these pieces of accessory equipment is a saw table assembly, which is fully described in the above entitled parent application, detachably mountable upon shaft 30 at the left end of the lathe frame 9.

Another device removably mounted on the support 30 is a table 31 which is used to carry the work during the sanding operation. At times this table is lowered across the lathe bed in position for use as shown in Figures 1, 2 and 4. At such times its forward end is supported by legs 33 which rest on the lathe bed. At other times the table may be oscillated about support 30 to an inoperative position wholly clear of the lathe bed, in which it will not in any degree interfere with the use of the lathe.

When it is desired to use the sanding disk to perform a jointing function, a special jointing fence 35 is employed. This fence is also instantly adjustable between retracted and operative positions. Figure 1 shows the fence in its operative position and Figure 2 shows it elevated about support 30 as a fulcrum in its retracted position. The fence 35 is recessed at 36 to receive the disk 25 and its forward and rear guiding surfaces project differentially to provide a shoulder at 37 aiding in the guidance of the work notwithstanding-

- ing the depth of cut made by the disk in a given transfer of work, (see Figure 3). Within limits, the exact depth of cut is subject to regulation, the jointer being provided with a rotatable pin 38 held in adjustment by set screw 39 and having an eccentric projection 40 which engages in an aperture 41 of the headstock bracket 11.
- By rotating the pin 38 with a screw driver, the exact extent to which the abrasive sheet 26 projects from the forward face 42 of the fence 35 may be regulated, whereby very accurately to control the exact effect of the sander upon the work.
- As a piece of jointing apparatus the sander has proven to be exceptionally effective since it not only dresses the work but leaves it with a smooth finished surface. In addition, it is far safer for the workman than any previous known jointer.
- It is to be noted that the fence 35 and the sanding table 34, as well as the sanding disk 25 may be almost instantly removed entirely from the apparatus, leaving the lathe completely unobstructed to receive any work within its capacity.
- I claim:
25. 1. In a device of the character described, the combination with a spindle and a sanding disk having an abrasive surfacing, of a table support disposed rearwardly of the spindle, a table pivotally mounted upon said support and adapted to lie across the face of the disk, and a fence also pivotally mounted on said support, recessed to receive said disk, and provided with axially offset work guiding surfaces at opposite sides of the disk.
  30. 2. In a device of the character described, the combination with a spindle and a sanding disk having an abrasive surfacing, of a table support disposed rearwardly of the spindle, a table pivotally mounted upon said support and adapted to lie across the face of the disk, and a fence also pivotally mounted on said support, recessed to receive said disk, and provided with axially offset work guiding surfaces at opposite sides of the disk, together with means for adjusting with reference to the disk the free end of said fence, whereby to vary within narrow limits the amount of work which will be removed by the disk in a traverse thereof by the work.
  35. 3. In a device of the character described, the combination with a jointing tool and a stepped fence operatively associated therewith, of means for mounting said fence at one of its ends, and an adjusting means remote from the mounting means comprising a pin rotatably mounted and provided with an eccentric point and an apertured part with which said point is engageable to spring said fence in one direction or the other according to the position of said pin.
  40. 4. In a device of the character described, the combination with a spindle and a planiform disk provided with an abrasive sheet adhesively held thereon, of a table support disposed rearwardly of the spindle, a table fulcrumed thereon and adapted to lie across the face of said disk in its operative position, a fence also fulcrumed on said support and pivotally movable thereon, recessed to receive said disk, and provided with axially offset work guiding surfaces at opposite sides of the disk, together with adjusting means operatively connected to move said fence with reference to said disk within narrow limits
  45. 5. In a device of the character described, the combination with a rotary tool having a work engaging face, of a pintle mounted rearwardly of said tool and work guiding and supporting means mounted on said pintle, each of said means being independently movable to and from operative positions relative to said face.
  50. 6. In a device of the character described, the combination with a rotary tool having an abrasive working face, a pintle maintained rearwardly of said tool, a fence pivoted at one end on said pintle and capable of movement to and from an operative position adjacent said working face, a work supporting table pivoted on said pintle and independently movable relative to said fence and adapted to lie across the face of said tool in its operative position.
  55. 7. In a device of the character described, the combination with a rotary tool having a planiform working face, of a pintle mounted rearwardly of said tool, a fence recessed to receive said working face and provided with axially offset work guiding surfaces at the opposite sides of said face, said fence being fulcrumed on said pintle and capable of independent movement to and from an operative position about said working face, and a work supporting table pivoted on said pintle and independently movable in a plane substantially parallel to that of said fence and adapted to lie across the face of said tool in its operative position.
  60. 8. In a device of the character described, the combination with a lathe bed and a spindle, of a rotary tool provided with a planiform abrasive working face mounted on said spindle, a pintle mounted on said lathe bed at the rear thereof, work supporting and guiding means pivoted on said pintle and movable to and from positions of use relative to said tool, one of said means being provided with a secondary support engaging the lathe bed when said means is in an operative position.
  65. 9. In a device of the character described, the combination with a lathe bed and a spindle, of a disk having an abrasive face thereon positioned on said spindle, a pintle carried by said lathe bed at the rear thereof, a recessed fence pivoted on said pintle for movement to and from an operative position about said disk, a work supporting table carried by said pintle and capable of independent movement thereon relative to said fence and in its operative position adapted to lie across the face of said disk, and a supporting leg connected with the under surface of said table and in its operative position engaging the bed of said lathe to maintain said table in position before said disk.
  70. 10. In a device of the character described, the combination with a substantially horizontal shaft and a disk mounted thereon for rotation in a vertical plane, said disk having an abrasive face, of a work supporting table disposed adjacent the face of the disk, and a fence recessed to receive the disk and having surfaces limiting the engagement with said disk of work on said table, said fence being mounted for bodily removal from the path of such work.

OLE EVINRUDE.
